US00D448016B1

(12) United States Design Patent **(10) Patent No.:** **US D448,016 S**
Arpe **(45) Date of Patent:** **** Sep. 18, 2001**

(54) WIRELESS HEADPHONES FOR HANDS-FREE TELEPHONING

D. 357,479 * 4/1995 Coomans D14/223
4,727,599 * 2/1988 Rappaport et al. ..... 379/430 X
5,793,865 * 8/1998 Leifer ..... D14/206 X

(75) Inventor: **Michael Arpe**, Kiel (DE)

* cited by examiner

(73) Assignee: **DeTeWe AG & Co.**, Berlin (DE)

(**) Term: **14 Years**

(21) Appl. No.: **29/128,528**

Primary Examiner—Nanda Bondade
(74) Attorney, Agent, or Firm:—Herbert L. Lerner;
Laurence A. Greenberg; Werner H. Stemmer

(22) Filed: **Aug. 24, 2000**

(57) CLAIM

(30) Foreign Application Priority Data

The ornamental design for wireless headphones for hands-free telephoning, as shown and described.

Feb. 25, 2000 (DE) 400 02 130

(51) LOC (7) Cl. **14-01**

DESCRIPTION

(52) U.S. Cl. **D14/206**

(58) Field of Search D14/137-138,

D14/140, 142, 147, 148, 205, 206, 223,
192, 240; 181/129, 130; 379/430, 431,
433, 419-420, 428, 440; 381/183, 187

(56) References Cited

FIG. 1 is a front perspective view of the wireless headphones for hands-free telephoning; and,

FIG. 2 is a side perspective view thereof.
